[57] CLAIM

The ornamental design for a disc player, as shown and described.

DESCRIPTION

FIG. 1 is a perspective view of a disc player showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational views thereof, and,

FIG. 8 is a perspective view thereof, wherein the lid portion is in the open position.

The broken line showing of the inside portions is for illustrative purpose only and forms no part of the claimed design.

The portions of the inside views which are not visible in FIG. 8 form no part of the claimed design.
